UNITED STATES PATENT OFFICE

CHARLES E. SPITZER, OF COOPERSBURG, PENNSYLVANIA

HAMMER FOR HAMMER MILLS

Application filed September 13, 1928. Serial No. 305,756.

This invention is a hammer for use in the hammer type of grinding or pulverizing mills and is intended more particularly for use in pulverizing grain, although it is adapted for use in reducing other material. The invention provides a hammer which may be used for a long time without being resharpened or having its working face renewed and consists in certain novel features which will be hereinafter first fully described and then more particularly defined in the appended claim.

In the accompanying drawing:

Figure 1 is a sectional elevation of a portion of a gang of hammer mill disks having my improved hammer applied thereto;

Fig. 2 is a front elevation of the same;

Fig. 3 is an enlarged side view of the hammer removed, and

Fig. 4 is an edge view of the hammer.

Hammer mills comprise a casing into which the material is fed and which has an outlet in its lower portion through which the pulverized material may discharge. The casing is of a general cylindrical formation and as it, in itself, constitutes no part of my invention and is not necessary to an understanding of the same, it is omitted from the accompanying drawing. Rotatably mounted in the casing is a shaft, indicated at 1, upon which is secured a plurality of disks 2 which are held in parallel spaced relation by spacers or washers 3 of any suitable type. Pivottally mounted between adjacent disks are hammers 4, any number of which may be employed and which are free to swing about their respective pivots so that, as the shaft and the disks are rotated, the hammers will be caused to impinge forcibly upon the material through centrifugal action so as to cut through and pulverize the same.

According to my invention, the hammer comprises a shank 5 having plane side faces which are parallel and disposed parallel with the adjacent disks, the shank being provided near its inner extremity with an opening 6 through which the pivot, indicated at 7, may be passed. The outer end portion of the hammer is laterally enlarged to provide a head 8 and the side edges of the head are formed

with corrugations or notches 9 which extend diagonally with respect to the side faces of the hammer, as shown most clearly in Fig. 4, the corrugations upon the opposite edges extending in opposite directions so that either edge may be presented forwardly to act upon the material without requiring any change in the mode of operation. The symmetrical outline of the hammers permits them to be fitted between and attached to the disks without requiring special care to be observed in selecting the hammers and placing them.

In operation, the disks are rotated at high speed in the usual manner as the grain or other material is fed through the top of the casing and the hammers will swing through the material to cut the same and quickly pulverize it to a size which will permit the particles to pass through the screen outlet of the casing. Any particles which are not thoroughly pulverized and reduced will continue to move around within the casing and will be repeatedly acted upon by the hammers so that eventually all the material will be reduced to the desired pulverized condition. When one corrugated or working edge of the hammer has been worn down so as to be no longer effective, it is not necessary to at once sharpen the edge or renew the same inasmuch as the hammer may be simply removed and reversed and then replaced, presenting the formerly inactive edge to the grain so that the use of the mill will not be suspended. My improved hammer may be produced at a low cost and may be installed in any existing mill without requiring any structural changes therein.

Having thus described the invention, I claim:

An elongated flat parallel sided reversible milling hammer comprising an alining shank and head in the same plane, the edges of the head being outwardly curved and diagonally corrugated, the corrugations of one edge extending in a reverse direction to the corrugations of the opposite edge.

In testimony whereof I affix my signature.

CHARLES E. SPITZER. [L. S.]
